A. B. RIPPE.

DETACHABLE DEVICE FOR OPERATING AWNING WINCHES.

APPLICATION FILED DEC. 28, 1918.

1,345,027.

Patented June 29, 1920.

FIG. 1.

FIG. 2.

FIG. 3.

INVENTOR
AUGUST B. RIPPE,

BY *J. H. McInerney*,
ATTORNEY

UNITED STATES PATENT OFFICE.

AUGUST B. RIPPE, OF SALT LAKE CITY, UTAH.

DETACHABLE DEVICE FOR OPERATING AWNING-WINCHES.

1,345,027.

Specification of Letters Patent. Patented June 29, 1920.

Application filed December 28, 1918. Serial No. 268,611.

To all whom it may concern:

Be it known that I, AUGUST B. RIPPE, a citizen of the United States, and a resident of Salt Lake City, the county of Salt Lake, 5 and the State of Utah, have invented a certain new and useful Detachable Device for Operating Awning-Winches, of which the following, together with the accompanying drawings, forms a full, clear, and exact specification, which will enable others skilled in the art to which it appertains to make and use the same.

My invention relates to a detachable device for operating the winches in common 15 use for raising and lowering awnings, and especially to those winches of the so-called self-locking worm gear type.

The principal objects of this invention are: first, to provide a downwardly extending 20 rod for operating awning winches, means being provided whereby the rod may be quickly attached or detached, thus making it possible to use one rod for a considerable number of awnings and effecting a 25 great saving in the first cost of the awning; second, to provide a device which shall be efficient, simple and durable, besides economical in cost; third, to eliminate the unsightly permanent shafts and the so-called "crank 30 boxes" such as are in general use at the present time, thus improving the appearance of a building and avoiding damage suits due to passers-by colliding with the crank 35 boxes; fourth, to make it difficult for unauthorized persons to tamper with the awnings; and fifth, to make it possible to apply the present device to existing winches without making any changes in the winches 40 themselves.

In order to clearly show the application of this device, the construction of ordinary awnings will be described first.

Awnings in common use at the present time are so made as to have a rod of wood or 45 other suitable material fastened to the canvas at the lower edge of the awning, the said rod being supported on arms which are hinged to the building. The upper edge of the awning is fastened to a roller which is 50 journaled in brackets fastened to the building and so arranged that the awning may be wound up on the roller. At one end, the roller carries a rigidly mounted worm wheel which meshes with a worm whose threads 55 have a comparatively small pitch, the worm wheel and worm being suitably mounted in

a casing and forming what is well known as a "winch of the self-locking worm gear type."

The worm of the winch usually has a shaft 60 portion which projects outside the casing and at its end carries a universal joint, connecting the worm shaft to an operating shaft standing at any required angle with relation to the worm shaft. The operating shaft 65 usually extends downwardly to a point easily reached by a person desiring to raise or lower the awning, and the lower end of the operating shaft is journaled in what is usually termed a "crank box" the latter being 70 permanently attached to the building and provided with means whereby the operating shaft may be rotated, thus imparting motion to the universal joint, and through the winch, to the awning roller. The operating 75 shaft and the crank box mar the appearance of a building and in the case of a building where the crank box must be attached to brick or stone, the crank box is decidedly objectionable owing to the impossibility of making a durable fastening.

The mechanism so far described, forms no part of the present invention. Briefly, the invention comprises a stem having suitably disposed hooks and a separate rod having 85 hooks adapted to interlock with the hooks on the stem, so rotative motion may be communicated from the rod to the stem. The stem is adapted for fastening to the universal joint of an ordinary awning winch in 90 the place of the usual operating shaft, while the operating rod may be attached to, or detached from, the stem, as the user may desire.

The features of this invention, on which 95 protection is desired, are collectively grouped in the appended claims.

In the drawing,

Figure 1, represents a perspective view of the stem and its hooks;

Fig. 2, a perspective view of the hooks on the operating rod;

Fig. 3, an elevation of the complete device, drawn to a reduced scale; and

Fig. 4, a perspective view, drawn to a 105 still further reduced scale, and showing the device in the act of being used on the front of a building.

Referring to the drawing, 10 illustrates a stem provided with hooks; these may be two 110 in number and they may originate near the lower end of the stem. The hooks, 11 and

12, may lie in the same plane and extend outwardly and upwardly with relation to the stem, as clearly shown in Fig. 1.

The operating rod 17, at its upper end, is provided with hooks; these hooks may also be two in number and they may have their standing portions 14 (Fig. 2) extend outwardly, and diverge, from a common origin at the end of the rod 17. The point portions 15, of the hooks, may extend backwardly from the turns 16, and may diverge from the standing portions 14 as clearly shown in Fig. 2.

At 25, in Fig. 4, is shown an ordinary awning winch in the position usually occupied with relation to the awning. At 26 is that part of the universal joint carried by the worm shaft of the winch, and at 27 is the part to which the stem 10 is fastened.

In the present instance the universal joint is shown as consisting of the forks 26 and 27 with a member between them to which each of the forks is pivoted in a manner that is well known and hence need not be further described here. One method of fastening the stem 10 to the part 27 is shown in Fig. 3, and in this instance the part 27 is bored to receive the upper part of the stem 10 which is held in place by a pin 13^a which passes through holes in the part 27 and through the hole 13 (Fig. 1) in the stem.

In using this device, the hooks on the rod 17 are hung over the hooks on the stem 10 as shown in Figs. 1 and 4, the position of the hooks belonging to the rod 17 being indicated by the dotted lines in Fig. 1. The rod 17 may be readily rotated by means of the handle 19 and the crank 18 in the hands of the user.

Having described my invention, what I claim is:

1. In a detachable device for operating awning winches, a stem adapted to be fastened to a winch in place of the customary operating shaft, hooks projecting from the said stem, a separate rod having hooks which originate at one end of the rod, extend outwardly from the rod, turn, and extend backwardly, the said rod hooks being adapted to interlock with the said stem hooks for the purpose specified.

2. In a detachable device for operating awning winches, a stem adapted to be fastened to the driving member of a winch, hooks projecting outwardly and upwardly from the lower part of the said stem, a rod separate from the said stem, hook standing portions originating at an end of the said rod and extending away therefrom, turn portions adjacent the standing portions

point portions adjacent the turn portions, the said standing portions, turn portions and point portions forming hooks adapted to interlock with the said stem hooks for the purpose of attaching the said rod to the said stem.

3. In a detachable device for operating awning winches, a rotatable rod, hook standing portions rigidly projecting from the said rod, turn portions adjacent the standing portions, point portions adjacent the turn portions, the said standing portions, turn portions and point portions forming hooks, other hooks with which the first-named hooks are adapted to co-act, a stem for supporting the said other hooks, and means for fastening the said stem to the motion-receiving portion of an awning winch.

4. In a detachable device for operating awning winches, a stem projecting from the motion-receiving portion of a winch, hooks projecting from the said stem, a rod having hook standing portions projecting therefrom, turn portions adjacent the standing portions, point portions adjacent the turn portions, the said standing portions, turn portions and point portions being adapted to co-act with the stem hooks, and means for rotating the said rod.

5. In the device described, a stem adapted for fastening to the motion-receiving portion of an awning winch, hooks projecting from the said stem, a rod separate from the said stem, hooks projecting from an end of the said rod, the said hooks having standing portions extending outwardly from the said rod with backwardly extending point portions, the said rod hooks being adapted to co-act with the said stem hooks for the purpose specified.

6. A hook having a standing portion, a turn portion, and a backwardly extending point portion, means for supporting the said hook; a separate member having means for engaging the said hook and means for fastening the said separate member to an awning winch, the said hook and member being adapted to co-act for the purpose specified.

7. A hook, comprising a stem adapted to form a continuation of the driving member of an awning winch, a standing portion extending outwardly from the said stem, a point portion extending from the said standing portion, and a separate member having means adapted to co-act with the said hook for the purpose specified.

In testimony whereof I sign my name hereto.

AUGUST B. RIPPE.
